UNITED STATES PATENT OFFICE

BENJAMIN HARRISON FLYNN, OF AMARILLO, TEXAS

METHOD AND FORM FOR CONCRETE HIGHWAY CONSTRUCTION

Application filed February 5, 1930. Serial No. 426,076.

In constructing concrete highways with advanced methods, heavy rails are laid along the right-of-way and anchored to the ground, equipment is advanced along the rails and the latter are left in place along the finished concrete until the latter has set for a predetermined period, usually for a night and a day. Hence, it is necessary for the paving contractor to have on hand sufficient of the heavy rail sections for two days' run, half of them being used for one day's run and the other half remaining at the edges of the roadway finished on the previous day. Consequently, these heavy and cumbersome rail sections mean a great deal of expense for purchase and further expense and trouble when hauling along the roadway and when moving equipment from one job to another.

It is the object of my invention to make unique provision whereby it is only necessary to have on hand substantially half the number of heavy rail sections, the others being replaced by relatively light, inexpensive and easily handled forms.

With the foregoing in view, the invention resides in the novel subject matter herein-after described and claimed, description being accomplished by reference to the accompanying drawing.

Fig. 1 is a perspective view showing a portion of the form against a portion of one of the track rails.

Fig. 2 is a view showing one of the form sections in horizontal section and illustrating the adjacent rail in top plan view.

Fig. 3 is a transverse sectional view on line 3—3 of Fig. 2.

Fig. 4 is a perspective view showing the connection between adjacent ends of form sections.

Fig. 5 is a diagram hereinafter explained.

In the drawing above briefly described, the numerals 6 denote conventional, heavy, track-forming rails which are ordinarily used also as forms between which to cast the concrete, said rails 6 being provided with stake sockets 7 to receive anchoring stakes 8 which are driven into the ground.

The numerals 9 have reference to horizontally elongated concrete form sections of

much lighter and less expensive construction than the rails 6. Each form section 9 is preferably formed from a metal channel so that it embodies a vertical side wall 10 and flanges 11 and 12 projecting laterally from the upper and lower edges of said wall. Between the ends of the flanges 11 and 12 and abutting the latter, are vertical struts 13 and 14 respectively which may well be formed from lengths of angle iron riveted or welded to the wall 10. A similar strut 15 is shown between the ends of the form section 9 and it will be understood that any desired number of such struts could be provided for reinforcing purposes. The struts 13 and 14 have notches 16 and 17 formed in their upper ends, and a short block 18 passes through the notch 16 and is secured by rivets 19 or other desired means to the flange 11. The outer end of the block 18 projects beyond the strut 13 to provide a tongue, and this tongue of any section 9 is receivable in the notch 17 of the next adjacent section.

At suitable points along the length of the form section 9, stake sockets 20 are secured to the wall 10 between the flanges 11 and 12, said flanges having notches 21 and 22 at the upper and lower ends of said sockets, allowing anchoring stakes 23 to be driven through the latter. The upper ends of the sockets 20 terminate below the flange 11 as seen in Fig. 3, allowing the upper end of the stakes 23 to occupy positions below the upper edge of the form section 9. Each of these form sections is preferably of the same height as the rails 6.

In carrying out one specific method in accordance with my invention, the rails 6 are laid and anchored to a sufficient extent for a day's run, as seen in diagram in Fig. 5. A grading machine 24 is now propelled along the rails to prepare the grade, discharging any removed earth at the sides of the proposed roadway. As the grader 24 advances, the form sections 9 are applied against the inner sides of the rails 6, behind said grader, said forms being anchored to the ground by the stakes 23. A conventional paving machine 25 is propelled along the rails 6 and forms 9 at a suitable distance behind the grader 24 for the purpose of mixing the con-

- crete and discharging it between the forms 9. Another machine 26, or possibly a number of them, are propelled along the rails 6 and forms 9 behind the paver 25, to properly distribute and finish the concrete. As all of the equipment which must travel upon the tracks or rails 6, passes, these rails are removed from engagement with the forms 9, leaving the latter in place to retain the finished concrete for the desired setting period. The removed rail sections are then re-laid and anchored in advance of the grader 24 in readiness for the latter to operate upon them. It will be seen that by thus transferring the heavy rail sections from points behind the equipment to points in advance thereof and leaving the form sections 9 to hold the concrete, it is not necessary for the contractor to have on hand as many of said rail sections. Consequently, his investment in equipment is reduced and he is saved trouble and expense in hauling the rail sections along a project and in moving his "outfit" from one location to another.
- If the grade is prepared by means other than the grader 24 operating upon the rails 6, these rails may be laid upon the prepared grade, the forms 9 secured in place against the inner sides of said rails, the paver 25 advanced along track and forms, the concrete finished, and rail sections behind the equipment removed and re-laid and anchored in front thereof.
- It will be seen from the foregoing that the invention is of great advantage both as to structure and method. Attention however may be invited to the fact that the various features herein disclosed may be considered as illustrative only, it being understood that numerous variations may be made within the scope of the invention as claimed.
- I claim:
1. In concrete highway construction, the steps of laying and anchoring sectional parallel rails to form a track, positioning concrete forms at the inner sides of said rails and anchoring said forms to the ground independently of said rails, propelling a paving machine along the track and finishing the concrete between the forms, removing the rail sections and leaving said forms anchored to the ground to retain the concrete during setting, and re-laying and anchoring the removed rail sections in advance of the paver.
  2. In concrete highway construction, the steps of laying and anchoring parallel sectional rails, propelling a work-performing machine upon said rails, positioning concrete forms at the inner sides of the rail sections behind the machine and anchoring said forms to the ground independently of said rails, removing the rail sections and leaving said forms anchored to the ground to retain the concrete during setting, and re-laying

and anchoring the removed rail sections in advance of the machine.

3. In concrete highway construction, the steps of laying and anchoring parallel sectional rails, propelling a grader along said rails and grading between them, positioning concrete forms at the inner sides of the rail sections behind the grader and anchoring said forms to the ground independently of said rails, propelling a paving machine along said rails behind the grader and spreading the concrete between the anchored forms, removing the rail sections behind said paving machine and leaving said forms anchored to the ground to retain the concrete during setting, and re-laying and anchoring the removed rail sections in advance of the grader.

4. In concrete highway construction, the steps of laying and anchoring parallel sectional rails, propelling a grader along said rails and grading between them, positioning concrete forms at the inner sides of the rail sections behind the grader and anchoring said forms to the ground independently of said rails, propelling a paving machine along said rails behind the grader and spreading the concrete between the anchored forms, propelling a concrete-finishing machine along said rails behind the paving machine, removing the rail sections behind said finishing machine and leaving said forms anchored to the ground to retain the concrete during setting, and re-laying and anchoring the removed rail sections in advance of the grading machine.

5. In concrete highway construction, the steps of positioning concrete forms at the inner sides of equipment-supporting track rails, anchoring said forms to the ground independently of said rails, pouring concrete between said forms and removing the track rails, leaving said forms anchored to the ground to retain the concrete during setting.

6. Concrete highway construction equipment comprising sectional weight-supporting rails upon which to operate a machine, sectional concrete forms adapted to be placed at the inner sides of said rails, means for anchoring the rail sections to the ground, and independent means for anchoring said forms to the ground, whereby rail sections behind the machine may be transferred to positions in front of said machine, leaving said forms for concrete retention.

In testimony whereof I have hereunto affixed my signature.

BENJAMIN HARRISON FLYNN.
